UNITED STATES PATENT OFFICE.

WILLIAM J. WOODS, OF BERKELEY, CALIFORNIA, ASSIGNOR OF THREE-FOURTHS TO
FRANK H. SEARLS, OF BERKELEY, CALIFORNIA.

EXPANSION-ENGINE.

1,281,736.

Specification of Letters Patent. Patented Oct. 15, 1918.

Application filed November 15, 1915. Serial No. 61,449.

To all whom it may concern:

Be it known that I, WILLIAM J. Woods, a citizen of the United States, and a resident of the city of Berkeley, county of Alameda, 5 and State of California, have invented certain new and useful Improvements in Expansion-Engines, of which the following is a specification.

The invention relates to improvements in 10 expansion engines for refrigerating or liquefying air and is equally as applicable to refrigerating or liquefying other gases or gaseous mixtures.

An object of the invention is to provide 15 an improved form of expansion engine for compressed air or other gases.

The invention possesses other advantageous features, some of which, with the foregoing, will be set forth at length in the following description, where I shall outline in full that form of the invention which I have selected for illustration in the drawings accompanying and forming part of the present specification. In said drawings I have 25 shown only one specific form of my invention, but it is to be understood that the invention is not limited to such form, since it may be embodied in a multiplicity of forms, each being a species of my invention.

30 Referring to said drawings:

Figure 1 is a somewhat diagrammatic representation of one form of refrigerating apparatus of my invention, part thereof being shown in section.

35 Fig. 2 is an elevation, partly diagrammatic, of one form of liquefying apparatus of my invention, part thereof being shown in section.

Fig. 3 is a longitudinal section through 40 the cylinder of the expansion engine of my invention which also serves as an air compressor.

Fig. 4 is a similar view of a modified form of the device shown in Fig. 3.

45 The cycle of operations which I employ in the refrigerating process, consists in compressing air, cooling the compressed air, admitting the cool and compressed air to a cylinder and allowing it to expand against a piston doing external and internal work, whereby it is further cooled, passing the cooled air through a refrigerating coil and conducting it back to the compressor where it is again compressed and passing it back 50 through the same cycle of operations. The 55

external work done by the expanding air is employed to assist in driving the circulating compressor.

In the liquefying cycle, the air passing into the expansion engine passes in one direction through an intercooler, through which the colder air from the expansion engine passes in the opposite direction. The two streams of air are kept apart so that they do not mix, but they are in thermal communication, the colder air acting to reduce the temperature of the warmer compressed air, so that when such air expands in the cylinder of the engine, its temperature is greatly reduced. As the air is continuously circulated through the system its lower temperature is continually reduced until liquefaction occurs. I have found it advisable, however, in some instances, to withdraw air from the liquefying cycle 65 previously described and to subject this air to a greater pressure than that which obtains in the above liquefying cycle in order to facilitate initial liquefaction. This air is withdrawn from the cycle at a point of 70 low temperature, so that the removed air is substantially dry, the greater proportion of the moisture having been frozen therefrom.

I shall first describe the refrigerating apparatus shown in Fig. 1. This apparatus 85 comprises an air compressor 2, which I have termed the circulating compressor. The compressed air from the compressor 2, the temperature of which is raised by the compressing action, passes through the cooling 90 coil 3, which is suitably cooled externally by dripping water or other means, so that heat is extracted from the air as it passes through. The cooled compressed air then passes through the conductor 4 to the inlet 95 side of the expansion engine 5, where its inflow into the cylinder 6 is controlled by the inlet valve 7. The compressed air expands and does work in the cylinder by driving the piston 8, whereby its temperature is further reduced and the cold expanded air passes through the outlet port, which is controlled by the valve 9, through the refrigerating coil 12 and back to the inlet side of the circulating compressor 2. The valve 100 105 stems extend through tubes 10, which are of such length that the packing nuts which close the ends of the tubes lie externally of the heat insulating covering with which the cylinder is invariably surrounded. In the 110

particular embodiment shown in Fig. 1 the inlet valve 7 is operated by a cam or eccentric 81 arranged on the shaft 82 which is geared to the engine shaft 27, and the outlet valve 9 is operated by a cam or eccentric 83 on the same shaft 82 through the medium of a lever 84. The refrigerating coil 12 is arranged in the room or chamber to be maintained at a low temperature. Air is fed into the closed cycle by the feed compressor 13 which is preferably connected to the cooling coil 3 adjacent the circulating compressor. The feed compressor is operated only for a short time during the starting of the apparatus until the closed cycle becomes sufficiently charged, when the feed compressor may be stopped. Should leakage or liquefaction occur in the closed cycle it will be necessary to operate the feed compressor intermittently to compensate therefor.

The cranks of the circulating compressor and the expansion engine are preferably connected so that the power developed in the expansion engine may be employed to assist in driving the compressor. The two devices may have a common crank case 14 which is air tight so that any air or gas escaping from the cylinder of either the compressor or the engine by leakage past the pistons will not escape from the cycle, but will find its way back to the compressor through some device, such as the conduit 15 connecting the interior of the case with the cycle adjacent the inlet to the circulating compressor. This arrangement is valuable because dry air is necessary for the continuous successful operation of an air expansion engine and air once dried and introduced into the apparatus should be conserved therein as long as possible. The expansion engine embodies several improvements which greatly increase the efficiency of the cycle and which render the engine operative under all conditions. Heretofore, the engine piston has operated in the cylinder into which the cold air expands and the friction of the piston and piston rings has produced heat which was absorbed by the cold air, thereby raising its temperature and lowering the efficiency of the cycle. The temperature which obtains in the cylinder during refrigeration or liquefaction is very low and this has heretofore resulted in the freezing of the lubricating oil, and piston rings so that the engine has become inefficient and inoperative. In accordance with my invention, I arrange the piston and piston rings in a cylinder which is heat insulated from the cylinder in which expansion occurs, so that the heat developed by the friction of the reciprocating piston is not communicated to the cold air and so that the cold air will not freeze the piston rings in their seats. The cylinder 6 is formed of two parts 6^a—6^b securely fastened together and heat insulated from each other by a ring 16

of heat insulating material. The piston 8 is also formed of two parts 8^a—8^b securely fastened together. The piston part 8^a is formed of any suitable material and carries the piston rings 17 and the piston part 8^b is formed of wood or other heat non-conducting material. The piston part 8^a is always disposed within the cylinder part 6^a and does not move into contact with the cold cylinder part 6^b, which part constitutes the expansion chamber. The wood piston part 8^b, which is secured to the piston part 8^a by the rod 65, is movable freely within the cylinder of the expansion chamber and forms a wood piston against which the compressed air expands. The wood piston is of slightly less diameter than the cylinder, so that it does not frictionally engage the wall thereof and is separated from the wall by a thin film of air. The wood piston is of such length with respect to the length of the expansion chamber and the stroke of the piston, that a portion of it always lies within the cylinder part 6^b, thereby allowing only the thin film of the cold air to come in contact with the warm section 6^a of the cylinder. The lubricating oil is thereby prevented from freezing and the engine may be operated for long periods of time at high efficiency. The cylinder portion 6^b is to be covered exteriorly with heat insulating material, so that the heat from the surrounding atmosphere is not absorbed by it.

When desirable, the expansion engine and the circulating compressor may be embodied in a machine employing one cylinder, one end being used as the expansion engine and the other as the compressor. The piston and cylinder are constructed as heretofore set forth with the exception that the cylinder is closed at its lower end by a head 18 through which the piston rod passes and in which the compressor inlet and outlet valves 21 and 22 are arranged. This construction is shown in Figs. 3 and 4. For refrigerating purposes, the volume of the air compressor should be greater than the volume of the expansion engine on account of the greater density of the air as it expands in the cylinder of the expansion engine. To accomplish this difference in capacity and still embody the two mechanisms in one unit, the construction shown in Fig. 4 is employed. The construction shown in Fig. 3, however, is operative without contravening this statement and in such construction the pressure on expansion is reduced below atmosphere or below the low pressure of the cycle. In this construction (Fig. 4) an extension 23 of the wood piston 8^b which is of lesser diameter than the piston, extends through a stuffing box 24 arranged in the upper head of the cylinder, thereby reducing the volume of the air expansion cylinder.

In Fig. 2 I have shown an air liquefac-

tion apparatus. In apparatus of this type, the expansion engine cylinder is arranged horizontally, instead of vertically as in the refrigerating apparatus, so that the liquid will not flow down between the wood piston and the cylinder walls to the piston rings. In the liquefaction apparatus the compressed air from the cooling coil 8 passes through an intercooler 55 before it enters the expansion engine and the cold air from the expansion engine passes through the intercooler in the opposite direction. In this manner, the low pressure exhaust air from the engine will be warmed to, or near to, the normal temperature and the high pressure air from the compressor will be cooled down to near the temperature of the exhaust from the engine before it enters the cylinder of the engine to be further cooled by expansion, until by repetition of this stepping down process the temperature may be reduced to any degree of cold until liquefaction occurs. Liquefaction occurs in the cylinder of the expansion engine and also in the high pressure coils of the intercooler and the liquid formed in the intercooler flows to the engine cylinder and that liquid and such as is formed in the engine, drains through the outlet port into the vessel 56 whence it may be withdrawn at pleasure.

The intercooler comprises a casing 57 at the opposite ends of which are arranged closed heads 58 which are connected by tubes 59. The incoming compressed air flows through the tubes and into the engine and the cold expanded air passes through the casing 57 and around the outside of the tubes. The space between the tubes is preferably filled with porous heat conducting material, such as wire screen 81, so that the two air streams are in close thermal communication. The space between the tubes and the casing is filled with a heat insulating material 82 which is arranged to cause the exhaust air to pass among the tubes, instead of straight up. The intercooler, the liquid chamber and the engine exhaust and supply pipe are always covered with a thick covering of heat insulating material to prevent the access of external heat thereto, and the tubes through which the engine valve stems pass are made of such length that the packing nuts occur outside of the in-

sulation. In air liquefaction apparatus, the capacity of the circulating compressor 55 should be four times the capacity of the expansion engine, because the air at liquefying temperature is approximately four times as dense as the air at normal temperature.

I claim:

1. In an apparatus of the character described, an expansion engine having a cylinder formed of two thermally insulated cylinder parts, a metallic piston slidable in one cylinder part and a block of heat insulating material secured to the piston and slidable in the other cylinder part, the expansion of the air occurring in said second cylinder part.

2. In an apparatus of the character described, an expansion engine having a cylinder formed of two thermally insulated parts, a piston provided with piston rings slidable entirely in one cylinder part, and a block of heat insulating material of less diameter than the cylinder attached to the piston and extending into the second cylinder part.

3. In an apparatus of the character described, an expansion engine having a cylinder, a ring of heat insulating material dividing said cylinder into two parts, a metallic piston slidable in one of said parts only, and a block of heat insulating material secured to said piston and extending into the other part, said block being of such length that it does not move entirely into said first cylinder part.

4. In an apparatus of the character described, an expansion engine having a cylinder, a ring of heat insulating material dividing said cylinder into two parts, a metallic piston provided with piston rings slidable in one of said parts only, a block of heat insulating material secured to said piston and extending into the other cylinder part, the length of said block being such that on the stroke of the piston, it is not entirely withdrawn from said second cylinder part.

In testimony whereof, I have hereunto set my hand at San Francisco, California, this 8th day of November, 1915.

WILLIAM J. WOODS.
